SHOTGUN SHELL

Edward A. Sobolewski, 19850 State Line Road,
South Bend, Ind.

Filed Apr. 21, 1965, Ser. No. 84,895

Term of patent 14 years

(Cl. D30—1)

FIG. 2

FIG. 1

FIG. 4

FIG. 3

FIG. 5

I claim:

The ornamental design for a shotgun shell, substantially as shown.
